UNITED STATES PATENT OFFICE.

MILLIE HINMAN, OF BROOKLYN, NEW YORK.

DESIGN FOR A DRESS.

54,519.

Specification for Design.

Patented Feb. 24, 1920.

Application filed July 28, 1919. Serial No. 313,945. Term of patent 3½ years.

To all whom it may concern:

Be it known that I, MILLIE HINMAN, a citizen of the United States, and a resident of the borough of Brooklyn, in the city and State of New York, have invented a new, original, and ornamental Design for Dresses, of which the following is a specification, reference being had to the accompanying drawings, forming part hereof.

In the said drawings Figure 1 is a front view of a dress, turned slightly to one side, showing my new design, and Fig. 2 is a back view thereof.

I claim:

The ornamental design for a dress, as shown.

In witness whereof I have hereunto signed my name this 22nd day of July, 1919.

MILLIE HINMAN.
